UNITED STATES PATENT OFFICE

143,946

DESIGN FOR A BEVERAGE COASTER

Grant Wortman, Chicago, Ill.

Application September 11, 1945, Serial No. 122,021

Term of patent 7 years

(Cl. D44—7)

To all whom it may concern:

Be it known that I, Grant Wortman, a citizen of the United States, residing at Chicago, in the county of Cook and State of Illinois, have invented a new, original, and ornamental Design for Beverage Coasters, of which the following is a specification, reference being had to the accompanying drawing, forming part thereof.

Fig. 1 is a top plan view of a beverage coaster, showing my new design;

Fig. 2 is a section on the line 2—2 of Fig. 1; and

Fig. 3 is a section on the line 3—3 of Fig. 2.

I claim:

The ornamental design for a beverage coaster, as shown.

GRANT WORTMAN.
